CLAIM

The ornamental design for a pipe coupling support, as shown and described.

DESCRIPTION

FIG. 1 is a top perspective view of an embodiment of a pipe coupling support;

FIG. 2 is a bottom perspective view of an embodiment of a pipe coupling support;

FIG. 3 is a front view of an embodiment of a pipe coupling support;

FIG. 4 is a back view of an embodiment of a pipe coupling support;

FIG. 5 is a right side view of an embodiment of a pipe coupling support;

FIG. 6 is a left side view of an embodiment of a pipe coupling support;

FIG. 7 is a top view of an embodiment of a pipe coupling support;

FIG. 8 is a bottom view of an embodiment of a pipe coupling support;

FIG. 9 is a cross section view of an embodiment of a pipe coupling support;

FIG. 10 is an exploded view of an embodiment of a pipe coupling support prior to installation on a pipe coupler assembly; and,

FIG. 11 is an embodiment of a pipe coupling support installed on a pipe coupler assembly.
